(57) CLAIM

The ornamental design for a chair as shown and described.

DESCRIPTION

FIG. 1 is a front perspective view of a chair according to my new design.

FIG. 2 is a rear perspective view of the chair of FIG. 1.

FIG. 3 is a rear-left perspective view of the chair of FIG. 1; and,

FIG. 4 is a front-right perspective view of the chair of FIG. 1.

The dash-dash broken lines in the figures and the areas with translucent shading within the dash-dash broken lines show portions of the chair that form no part of the claimed design.
